ABSTRACT OF THE DISCLOSURE

A surface active compound selected from the group consisting of

and its sodium, potassium and ammonium salts, where R and R' are selected from the group consisting of aliphatic alkyl having 10 to 18 carbon atoms and aliphatic alkenyl having 10 to 18 carbon atoms;

R₁ and R₂ are a lower alkyl or together with the nitrogen atom on which they are attached constitute a saturated monocyclic heterocyclic group;

and n is an integer of 2 to 5.

Shampoo, hair dye and detergent composition containing these compounds. A process of conditioning and softening hair. A process of thickening acid aqueous solutions.

This invention relates to new asparagine derivatives having surface-active properties, to a process for their preparation and to hair treatment compositions containing them.

We have now found that certain related asparagine derivatives not only show surface activity, but possess other properties which are of considerable interest in relation to the treatment of hair.

The asparagine derivatives of the invention are compounds of the formula:

where R and R' are each an aliphatic hydrocarbon radical of 10-18 carbon atoms which can be the same or different; R₁ and R₂ are each a lower alkyl radical, which can be the same or different, or together with the nitrogen atom to which they are attached constitute a heterocyclic residue and n is an integer of 2-5 inclusive (especially 2 or 3), and sodium, potassium and acid addition salt thereof. Preferred compounds are those in which R₁ and R₂ are alkyl radicals of 1-4 carbon atoms, for instance methyl or ethyl radicals. Other preferred compounds are those in which R₁ and R₂, together with the nitrogen atom to which they are attached, constitute a saturated monocyclic heterocyclic residue, for instance a morpholino or piperidino radical.

Compounds of the invention possess not only remarkable detergent properties, but also good softening and conditioning properties for the hair. Thus they can be used to advantage in hair shampoo or hair dyeing compositions.

Moreover, in acidic aqueous solutions these compounds show a very pronounced thickening and gelling effect. Since products currently employed as thickeners or gelling agents generally do not possess in themselves any deter-

2

gent or hair treating property, it will be seen that compounds of the invention are particularly advantageous, and because of this combination of properties they have a very wide range of use, for example, in aqueous solutions of other surface-active substances, especially those of cationic or non-ionic character, and in aqueous solutions of dyes.

The compounds of the invention can be prepared by a process which comprises condensing maleic anhydride with an alkylene diamine of the formula:

where R', R₁, and R₂ and n have the meanings given above, satisfying the reaction product to obtain the corresponding sodium, potassium or ammonium salt, and reacting said salt with a primary fatty amine of the formula: R-NH₂ where R has the meaning given above.

Particularly appropriate alkylene diamines are, for example, N-dodecyl-N',N'-diethylethylenediamine, N-cetyl-N',N'-diethylethylenediamine, N-dodecyl-N',N'-diethyltrimethylenediamine, and β -(dodecylamino)ethylmorpholine.

Particularly appropriate fatty amines are, for example, decylamine and dodecyl amine. It has been found that excellent results have been obtained using as primary amine a mixture of fatty amines derived from copra acid or tallow acid, which yield a mixture of compounds of Formula 1 differing only in the value of the substituent R, the various R substituents being the various alkyl radicals present in tallow or copra acids respectively.

The invention is illustrated by the following examples.

EXAMPLE I

Preparation of the sodium salt of N²-[alkyl(tallow)]-N-(dodecyl)-N-(N',N'-diethylaminoethyl)asparagine

(1) Preparation of N',N'-diethyl-N-dodecyl-ethylenediamine.—There are mixed with stirring 2 moles of dodecyl bromide and 10 moles of N',N'-diethylethylenediamine (96.6%) the temperature being maintained below 50° C. At the end of several hours, the reaction is complete. There are then added 4.3 moles of potassium hydroxide in pellet form, with vigorous stirring. The excess of potassium hydroxide and the potassium bromide formed are separated by filtration. The excess of N',N'-diethyl-ethylenediamine is thereafter evaporated under reduced pressure, and the crude product thus obtained is washed with water and dried in vacuo on the water bath.

N',N'-diethyl-N-dodecyl-ethylenediamine is thus isolated in an almost quantitative yield and in a purity of 98%.

(2) Preparation of N-dodecyl-N-(N',N'-diethylaminoethyl) maleamic acid.—One mole of N',N'-diethyl-N-dodecyl-ethylenediamine is dissolved in 300 ml. of ethyl acetate.

To this solution is added with stirring, in an hour and a half, one mole of maleic anhydride in solution in 300 ml. of ethyl acetate, the temperature being maintained between 35° and 40° C. The solid which precipitates is separated, washed with ethyl acetate and dried in vacuo, and N-dodecyl-N-(N',N'-diethylaminoethyl)maleamic acid is isolated as a white, water-soluble powder in a yield of 80%.

(3) Addition of the primary amine derived from tallow fatty acids.—0.7 mole of N-dodecyl-N-(N',N'-diethylaminoethyl) maleamic acid is dissolved in 300 ml. of ethyl alcohol, and the solution is neutralised with a calculated quantity of concentrated aqueous sodium hydroxide solution.

There is then added 0.7 mole of a mixture of primary amines derived from tallow fatty acids, and the mixture

3

is heated at 65° C., for 11 hours. After evaporation of the alcohol, the product obtained takes the form of an oil dispersible in water, which contains 4% of unreacted primary amine.

EXAMPLE II

Preparation of the sodium salt of N²-[alkyl(copra)]-N-(cetyl)-N-(N',N'-diethylaminoethyl)asparagine

By proceeding in an analogous to Example I, N-cetyl-N-(N',N'-diethylaminoethyl)maleamic acid is obtained from N',N'-diethyl-N-cetyl-ethylenediamine and maleic anhydride. The desired product is obtained by the addition to the sodium salt of the maleamic acid of a mixture of primary amines derived from copra fatty acids in an analogous way to Example I.

EXAMPLE III

Preparation of the sodium salt of N²-[alkyl(tallow)]-N-(cetyl)-N-(N',N'-diethylaminoethyl)asparagine

By the process analogous to that described in Example I, this product is obtained by the addition of a mixture of primary amines derived from tallow fatty acids to sodium N-cetyl-N-(N',N'-diethylaminoethyl)maleamate.

EXAMPLE IV

Preparation of the sodium salt of N²-[alkyl(copra)]-N-(dodecyl)-N-(N',N'-diethylaminoethyl)asparagine

This product is obtained by reacting the mixture of primary amines derived from copra fatty acids with sodium N-dodecyl-N-(N',N'-diethylaminoethyl)maleamate in a process analogous to that described in Example I.

EXAMPLE V

Preparation of the sodium salt of N²-[alkyl(tallow)]-N-(dodecyl)-N-(morpholinoethyl)asparagine

By a process analogous to that described in Example I, there is obtained from dodecyl bromide and aminomethylmorpholine, β -(dodecylamino)ethylmorpholine.

The condensation of this diamine with maleic anhydride gives the corresponding maleamic acid which, after neutralisation with sodium hydroxide, is reacted with the mixture of primary amines derived from tallow fatty acids yielding the desired product in the form of an oil.

EXAMPLE VI

Preparation of the potassium salt of N²-[alkyl(tallow)]-N-(dodecyl)-N-(N',N'-diethylaminopropyl)asparagine

N',N'-diethyl-N-dodecyl-trimethylenediamine is first prepared by a process analogous to that described in Example I. Maleic anhydride is reacted with this diamine in solution in t-butyl alcohol. The maleamic acid thus formed is neutralised by an aqueous potassium hydroxide solution, and the potassium salt is reacted with the mixture of primary amines derived from the fatty acids of tallow. By evaporation of the solvent, the desired product is obtained in the form of a viscous oil.

EXAMPLE VII

Preparation of the sodium salt of N²-[alkyl(copra)]-N-(cetyl)-N-(N',N'-diethylaminopropyl)asparagine

This product is obtained by a process analogous to that described in Example VI. It takes the form of a viscous oil.

Examples VIII to XVI below illustrate the use of compounds of the invention.

EXAMPLE VIII

The following mixture is prepared:

Sodium salt of N²-[alkyl(tallow)]-N-(dodecyl)-N-(N',N'-diethylaminoethyl)asparagine—3 g.

Lactic acid, q.s. for pH 5.5

Water q.s. for 100 cc.

A transparent jelly is obtained.

4

EXAMPLE IX

In the same way, by mixing.

Sodium salt of N²-[alkyl(tallow)]-N-(cetyl)-N-(N',N'-diethylaminoethyl)asparagine—3 g.

5 Lactic acid, q.s. for pH 4.

Water, q.s. for 100 cc.

a translucent gel is obtained.

EXAMPLE X

There is prepared an aqueous solution containing:

The condensate obtained from 1 mole of tridecyl alcohol and 15 moles of ethylene oxide—7 g.

Diethanolamide of copra fatty acids—3 g.

15 Sodium salt of N²-[alkyl(tallow)]-N-(dodecyl)-N-(N',N'-diethylaminoethyl)asparagine—6 g.

Lactic acid, q.s. for pH 5.

Water, q.s. for 100 cc.

20 This solution is of oily consistency and when used as a shampoo imparts suppleness to the hair and makes it easy to comb. The viscosity of this shampoo is substantially higher than that obtained by replacing the compound of the invention with a cationic product in current use.

EXAMPLE XI

There is prepared a solution containing:

The condensate obtained from 1 mole of copra fatty alcohol and 12 moles of ethylene oxide—8 g.

Diethanolamide of copra fatty acids—4 g.

30 Sodium salt of N²-[alkyl(copra)]-N-(N',N'-diethylaminopropyl)asparagine—3 g.

Sodium salt of N²-[alkyl(tallow)]-N-(dodecyl)-N-(N',N'-diethylaminoethyl)asparagine—6 g.

35 Lactic acid, q.s. for pH 5.

Water, q.s. for 100 cc.

40 There is thus obtained a shampoo of viscous consistency which imparts suppleness to hair and makes it easy to comb. Moreover, the hair after having been washed with this shampoo does not exhibit any accumulation of electrostatic charge. The viscosity of this shampoo is clearly higher than that obtained in the absence of the compound according to the present application.

EXAMPLE XII

There is prepared a solution containing:

The condensate of 1 mole of octylphenol and 18 moles of ethylene oxide—7 g.

Diethanolamide of copra fatty acids—4 g.

Cetyltrimethylammonium bromide—2 g.

50 Sodium salt of N²-[alkyl(tallow)]-N-(cetyl)-N-(N',N'-diethylaminoethyl)asparagine—6 g.

Lactic acid, q.s. for pH 5.

Water, q.s. for 100 cc.

55 A thick solution is obtained. This product constitutes a shampoo which renders the hair very soft and makes it easy to comb.

EXAMPLE XIII

There are prepared—

(a) A solution containing:

Sodium bromate—15 g.

Water—60 g.

60 (b) An emulsion containing:

The condensate of 1 mole of cetyl alcohol and 5 moles of ethylene oxide—2 g.

Sodium salt of N²-[alkyl(tallow)]-N-(dodecyl)-N-(N',N'-diethylaminoethyl)asparagine—3 g.

Phosphoric acid, q.s. for pH 6.5

Water—15 g.

70 (a) and (b) are mixed at about 40° C. and make up 75 to 100 c. with water. There is thus obtained a creamy
